UNITED STATES PATENT OFFICE

171,497

TIRE

Paul E. Hawkinson, Minneapolis, Minn., assignor
to Paul E. Hawkinson Company, Minneapolis,
Minn., a corporation of Minnesota

Application September 15, 1951, Serial No. 16,659

Term of patent 14 years

(Cl. D90—20)

To all whom it may concern:

Be it known that I, Paul E. Hawkinson, a citizen of the United States, residing at Minneapolis, in the county of Hennepin and State of Minnesota, have invented a new, original, and ornamental Design for a Tire, of which the following is a specification, reference being had to the accompanying drawings, forming part thereof.

Referring to the drawings:

Fig. 1 is a perspective view of a tire showing my new design, certain of the parts being shown in full lines and others in dotted lines;

Fig. 2 is a transverse sectional view taken on the line 2—2 of Fig. 4;

Fig. 3 is a fragmentary side elevational view; and

Fig. 4 is a fragmentary top plan view thereof with the side wall immediately below the tread

area shown on the same plane as said tread area.

The dominant features of my design reside in the portions shown in full lines.

I claim:

The ornamental design for a tire, as shown and described.

PAUL E. HAWKINSON.
